UNITED STATES PATENT OFFICE.

CHARLES W. HAWTHORNE AND GEORGE J. RENNIE, OF BUFFALO, NEW YORK.

TURNTABLE.

Application filed March 12, 1920. Serial No. 365,170.

To all whom it may concern:

Be it known that we, CHARLES W. HAWTHORNE and GEORGE J. RENNIE, citizens of the United States of America, and residents 5 of the city of Buffalo, county of Erie, and State of New York, have invented certain new and useful Improvements in Turntables, of which the following is a full, clear, and exact description.

10 Our invention relates generally to turn tables and more particularly to that type of turn table used in rolling mill practice.

It is well known that steel ingots are larger at one end than at the other, due to 15 the draft in the mold. These ingots, as they come from the reheating furnace, are alternately arranged with respect to their larger ends. If the larger end is fed to the rolling mill, serious damage to the rolling 20 mill is very apt to result.

The principal object of this invention has been to provide means, which may be located in the furnace run table and by which the ingots, as they come from the furnace, may 25 be turned end for end, so that each ingot may be fed to the rolling mill with its smaller end toward the mill.

Another object has been to provide a device of this character which shall be very 30 compact in its design; one which shall not require an abnormal elevation of the ingot in turning, thereby greatly economizing in time; and one which is efficient in operation and easily controlled.

35 The above objects and advantages have been accomplished by the device shown in the accompanying drawings, of which:

Fig. 1 is a vertical, sectional elevation of 40 our device, showing it installed in a furnace run table.

Fig. 2 is a sectional elevation of the same taken on line 2—2 of Fig. 1.

Fig. 3 shows a diagrammatical development 45 of the cylinder of our device with its cam surfaces.

In the drawings 5 represents the I-beam and 6 the rollers of a furnace run table. These rollers are, of course, provided with the usual bearings and means for driving 50 them, but these bearings and driving means, for clearness, have been omitted from the

drawings. 7 are the guides of the run table.

Secured to the I-beams 5 of the run table is a supporting yoke 8. 9 is the plunger of our device which has the lower end of its 55 stem 10 disposed in and supported by the supporting yoke 8. 11 is the cylinder of our device which is rotatably and slidably disposed about the plunger 9. The portion 12 of the cylinder is bored to fit the stem 10 of 60 the plunger and the lower end of the cylinder is provided with a packing gland 4, whereby the joint between the plunger stem and the cylinder is properly sealed. The upper portion of the cylinder 10 is counterbored at 34 and the plunger head 13 is disposed in this counterbore. The upper end of the plunger head 13 is provided with suitable packing washers 14 and 15, held in place by a nut 16, screw threaded to the upper 65 reduced end 17 of the plunger head. The upper end of the cylinder 11 is provided with a flange 18 to which the table bed 19 is secured by suitable means. By means of the foregoing construction, a chamber 20 is 70 provided above the plunger head 13 and a chamber 21 having considerably less cross-sectional area is provided below the plunger 75 head 13.

Arranged centrally through the plunger 80 stem 10 is a recess 22 which extends from the bottom of the plunger to a point near its upper end. A port 23 extends from this recess 22 to the outside of the plunger stem 10 whereby the recess is in communication 85 with the chamber 21. An annular groove 24 is preferably provided at the point of union of the head 13 with the stem 10 of the plunger, and the port 23 preferably opens into this annular groove. By this means the cylinder will not be sealed against the admission of fluid when it is in its uppermost position. A screw threaded aperture 25 extends from the upper end of the recess 22 to the upper end of the plunger head 13 and 90 opens into the chamber 20. A pipe 26, having its upper end screw threaded, is passed up through the recess 22 and is screw threaded into the aperture 25. A T-fitting 27 is passed through the bottom of the supporting yoke 8 and is screw threaded into the lower end of the plunger stem 10, thus plac- 100

ing the T-fitting and its branch 28 in communication with the lower end of the recess 22 and the plunger stem. The pipe 26 is passed through the T-fitting and is suitably packed at the lower end of the fitting by means of a stuffing-box having a packing gland 29. At the lower end of the pipe 26 is disposed preferably a three-way valve 30. A pipe 31 for conducting fluid under pressure and a pipe 32 for carrying away the discharge fluid are connected to the valve 30. By means of the handle 33 of the valve, fluid under pressure may be conducted to the chamber 20 or may be discharged therefrom, depending upon the position of the handle 33. Suitable piping is connected to the branch 28 of the T-fitting 27 whereby fluid is conducted to the chamber 21. For reasons, to be hereinafter stated, the pressure within the chamber 21 may be constantly maintained.

Arranged about the outer circumference of the cylinder 11 is a plurality of cams by which the cylinder is rotated as it is raised and lowered. So as to reduce the necessary amount of travel, we have arranged the cam so that the cylinder is rotated through substantially one-half of its predetermined travel during its upward movement and the other half of its predetermined travel during its downward movement. In Fig. 3 where we show a development of the cylinder cams, 35, 36, 37 and 38 are the cams, 35 and 37 being alike and arranged diametrically opposite each other and 36 and 38 being alike and also arranged diametrically opposite each other. The upper end of the cylinder is supported by a stationary bearing yoke 39, carried by the I-beams 5 of the furnace run table. The outer surfaces of the cams 35, 36, 37 and 38 are finished so as to bear against the central bore 40 of the bearing yoke 39, thus providing bearings for the cylinder. Additional bearings for the cylinder are provided by the ribs 41, 42, 43 and 44.

Rigidly carried by the bearing yoke 39 are two oppositely arranged and radially disposed shafts 45, each secured in position preferably by means of a bolt 46. On the inner peripherally reduced end 47 of each of these shafts is rotatably mounted a roller 48. The outer periphery of the roller is preferably beveled to such a degree that its sides in a horizontal plane are substantially radial. These rollers are arranged to engage with the cams 35, 36, 37 and 38 and to produce the rotary motion of the cylinder as it is being raised and lowered.

The top of the turn table bed 19 is, of course, arranged slightly below the upper edges of the rollers 6 of the run table. Furthermore, it is necessary that the billets be moved vertically in order to clear the guides 7 of the run table before it is turned. For

convenience, we will describe the action of the cams 35 and 36 in connection with one of the rollers 48 only, it being obvious that the same action is produced by the cams 37 and 38 in connection with the other roller.

In Fig. 3, the broken circular lines represent the positions of the rollers relative to the cam surfaces; and, by reference to the representation of the roller at the extreme left of Fig. 3, it will be seen that the cam 35 is arranged with its upper end at some distance from the upper end of the cylinder, whereby, when the cylinder is moved upwardly, it will travel a considerable distance without rotating, whereby the billet carried by the table will clear the guides 7 before it is turned. Just as soon as the roller is in the relative position represented by the circle 48^a, it will strike the upper surfaces of the cam 35 and the cylinder will be rotated through substantially one-half of its predetermined travel or to a point where the roller has reached the position shown by the circle 48^b. The cam 36 is arranged so that its lower end slightly overlaps the lower end of the cam 35 and is arranged far enough above the cam 35 to allow the roller, when traveling over the last mentioned cam, to pass freely beneath the lower end of the cam 36. The lower end of the cam 36, however, extends over far enough so as to engage with the roller when it occupies the relative position shown by circle 48^c. As the cylinder moves downwardly the distance represented by the relative positions of circles 48^b and 48^c, it will move in a straight line. When, however, the roller is in the relative position shown by the circle 48^c, it will engage with the lower surface of the cam 36 and cause the cylinder to rotate through substantially the other half of its predetermined travel or to a position where the lower end occupies the relative position shown by the broken circle 48^d. The angularly arranged face of the cam 36 stops at some distance from the end of travel of the cylinder, so that the rotation of the cylinder will have been completed before the billet reaches the point where it must be lowered without being rotated. After the roller has reached the end of this angularly arranged surface of the cam 36 (the relative position shown by the broken circle 48^d), the cylinder will be allowed to move downwardly without being rotated until the roller has reached the relative position shown by the broken line 48^e. During this downward movement the roller will be guided by the vertical leg 49 of the cam 36. When the roller has reached the relative position shown by the broken circle 48^e, the cylinder will have been rotated through its entire predetermined travel and will have returned again to its normal lower position. The upper end of the cam 37 is arranged to slightly overlap the upper end

of the cam 36, and is located therefrom a sufficient distance to permit the free passage of the rollers 48. The cam 35 is, of course, arranged in a similar manner with respect to 5 the cam 38.

As hereinbefore stated, the branch 28 of the T-fitting 27 is connected with fluid under pressure, and the pipe 31, connected with the three-way valve 30, is also connected 10 with fluid under pressure. The cross-sectional area of the chamber 21 being less than the cross-sectional area of the chamber 20, the chamber 21 may be maintained constantly under hydraulic pressure, so that 15 when the pressure in chamber 20 is released, the cylinder will be automatically returned to its lowermost position by the pressure within the chamber 21 combined with the weight of the cylinder and the billet which 20 it supports. When the cylinder is in the position shown in the drawings, it will be maintained in its lowermost position by its weight and also by the pressure which is exerted within the chamber 21. When the 25 handle 33 of the three-way valve 30 is now operated to allow the fluid under pressure coming from the pipe 31 to enter the pipe 26 and chamber 20, the pressure within the chamber 21 will be overcome and the cylinder will be elevated until the lower edge 30 of the plunger head 13 comes in contact with the portion 12 of the cylinder. When the handle 33 is now operated so as to connect the pipe 26 with the discharge pipe 32, the constant pressure within the recess 22 in the plunger stem 10, together with the weight of the cylinder and supported billet, will cause the cylinder to be moved downwardly to its lowermost position. 35 During the upward and downward movements of the cylinder, as hereinbefore described, the cylinder with its billet will have been rotated through its entire predetermined travel.

While we have shown the use of hydraulic pressure for operating the cylinder and have described the chamber 21 as being maintained under constant hydraulic pressure, it is obvious that the pressure may be controlled by a suitable valve in both of the 45 chambers or the cylinder may be raised and lowered by any other suitable means. These and other modifications of the details herein shown and described may be made without departing from the spirit of our invention or the scope of the appended 50 claims, and we do not, therefore, wish to be limited to the exact embodiment herein shown and described, the form hereinbefore described being merely a preferred embodiment thereof.

Having thus described our invention, what we claim is:

1. A turn table comprising a vertically

supported plunger, a cylinder slidably supported by the plunger, a bed carried by the cylinder, hydraulic means for raising and lowering the cylinder, and cam means carried by the cylinder and arranged on its exterior surface for turning the cylinder. 65

2. A turn table comprising a vertically supported plunger, a cylinder slidably supported by the plunger, a bed carried by the cylinder, means for raising and lowering the cylinder, a plurality of disconnected cams arranged on the exterior of the cylinder, and means co-acting with the cams, whereby by the cylinder is rotated as it is being raised and lowered. 70 75

3. A turn table comprising a vertically supported plunger, a cylinder slidably supported by the plunger, a bed carried by the cylinder, means for raising and lowering the cylinder, cams formed on the exterior of the cylinder, and stationarily arranged rollers engageable with the cams, whereby the cylinder is rotated as it is being raised and lowered. 80 85

4. A turn table comprising a vertically supported plunger having a central opening restricted at its upper end and a reduced lower portion, a cylinder slidably supported by the plunger, a bed carried by the cylinder, a pipe extending through the opening and secured in the restricted end thereof, whereby the cylinder may be raised by hydraulic pressure, the opening in the plunger being connected near its upper end with the exterior of the reduced portion of the plunger, means connected to the lower end of the opening, whereby the cylinder may be positively lowered by hydraulic pressure, and means controlled by the axial movement of the cylinder for rotating the cylinder. 90 95 100 105

5. A turn table comprising a vertically supported plunger, a cylinder slidably supported by the plunger, a bed carried by the cylinder, means for raising and lowering the cylinder, a bearing yoke for the cylinder, rollers carried by the yoke, cams formed on the cylinder and engageable with the rollers, whereby the cylinder is rotated as it is being raised and lowered. 110

6. A turn table comprising a vertically supported plunger, a head for the plunger, a cylinder supported by the plunger, a bed carried by the cylinder, thus forming a chamber above the plunger head and also a chamber below the plunger head of less cross-sectional area than the upper chamber, means for conducting fluid under pressure to the chambers, and means carried by the cylinder for turning the same during its upward and downward travel. 115 120 125

7. A turn table comprising a vertically supported plunger, a head for the plunger, a cylinder supported by the plunger, a bed

carried by the cylinder, thus forming a chamber above the plunger head and also a chamber below the plunger head of less cross-sectional area than the upper chamber, means for conducting fluid under pressure to the chambers, a bearing yoke for the cylinder, rollers carried by the yoke, cams

formed on the cylinder and engageable with the rollers, whereby the cylinder is rotated as it is being raised and lowered. 10

In testimony whereof, we have hereunto signed our names.

CHARLES W. HAWTHORNE.

GEORGE J. RENNIE.
